UNITED STATES PATENT OFFICE.

JOHN T. DENNY, OF CROMARTIE, NORTH CAROLINA.

MAIL-BOX.

No. 903,362.

Specification of Letters Patent.

Patented Nov. 10, 1908.

Application filed January 29, 1908. Serial No. 413,223.

To all whom it may concern:

Be it known that I, JOHN T. DENNY, a citizen of the United States, residing at Cromartie, in the county of Robeson and State of North Carolina, have invented a new and useful Mail-Box, of which the following is a specification.

This invention relates to mail boxes designed especially for rural delivery service; and has for its object to provide a strong, sufficiently water tight receptacle, simple in construction and operation and arranged to automatically display a signal when there is mail in the box for either owner or carrier and to lower said signal when the box is empty.

By the use of this improved mail box, time and labor are saved the carrier as he need not stop unless the signal is displayed which is operated automatically before mail can be deposited in the box, and remains in sight until the contents of the box have been collected. The lowering of the signal is also automatic and positive and caused when the collecting door is opened to remove the mail.

With these and other objects in view the invention comprises the novel construction, combination and arrangement of parts hereinafter described and claimed, reference being had to the accompanying drawing forming a part of this specification, in which—

Figure 1 is a perspective view of the improved mail box; Fig. 2 is a face view of the same showing the drop opening exposed and the signal flag elevated; Fig. 3 is a similar view of the box with the collecting opening partly uncovered; Fig. 4 is a like view illustrating the collecting opening wholly uncovered, the signal flag lowered, and the drop opening closed; and Fig. 5 is a sectional view of one end of the mail box on the line 5—5 of Fig. 1 looking in the direction of the arrow.

Similar reference numerals are used for the same parts in all the figures.

The mail box comprises a preferably cylindrical casing 1 of any approved length and diameter closed tightly at one end 2 in any suitable way and provided at its opposite end 3 with the various means for covering and uncovering the mail depositing and collecting openings, operating the signal flag and locking the collecting door in closed position.

Extending entirely across the cylinder 1 at its end 3 in a horizontal direction is a flat plate 4, the lower edge 5 of which is coincident with the horizontal diameter of the cylinder 1. The plate 4 extends upwardly about two thirds the radius of the cylinder thus leaving a space 6 of sufficient size above it for the deposit of mail. On the bottom edge of the fixed plate 4 is a lug 7 having an axial opening for a pivot pin 8 common to the two oscillating doors or closures 9 and 10 for covering respectively the depositing and collecting openings 6 and 11.

The closure 9 is a flat substantially semi-circular plate situated outside the fixed plate 4 with a portion of one side removed so that when turned about the pivot pin 8 to expose the drop opening 6 the edge 12 of said plate will coincide with the adjacent upper edge of the fixed plate and open the deposit slot 6 to its full extent. See Fig. 2. The outer curved edge of the closure 9 lies close to the inner wall of the cylinder 1 and is folded over or otherwise fastened to a circular ring 13 concentric with the pivot pin 8. To the ring 13 is secured the staff 14 of the signal flag 15, in line with the diametrical edge of said closure. Fixed to the closure 9 in line with the flag staff 14 but on the opposite side of the pivot pin 8 is a rod 16 extending a short distance beyond the side of the mail box and provided on its end with a weight 17. On one side of the mail box is a spring catch 18 in position to retain the rod 16 when the closure 9 is moved to fully cover the drop opening 6 as clearly shown in Figs. 1 and 4. In this position of the closure the signal flag 15 is depressed and out of sight of the mail carrier and the owners of the box.

The closure 10 of the collecting opening 11 is a semi-circular plate on the inner side of the fixed plate 4 and has its peripheral edge close to the inner surface of the cylinder and secured to a circular ring 19 in the same way as the closure 9 is attached to the ring 13. The closure 10 may extend a short distance across the diametrical line so that the common pivot pin 8 can pass through it. See Figs. 4 and 5. Hinged to the fixed plate 4 in the space between the edge 12 of the closure 9 and the cylinder 1 is a hasp 20, the lower free end of which projects below the lower edge of said plate 4 and is provided with a slot 21 to receive a

staple 22 on the closure 10 when the latter is in position to cover the delivery opening 11. A padlock 23 engages the staple 22 to prevent any unauthorized persons opening 5 the box. If preferred a lock 24 riveted to the inner surface of the cylinder may be substituted for the padlock and be of any preferred type. The key hole 25 for this lock will be made through the side of the 10 cylinder 1 as represented in Fig. 1.

The mail box is supported with its axis in a horizontal position and fastened by means of a suitable bracket 27 riveted on the under side of the box bolted to the upper end of a 15 post 28, the top rail of a fence or in some other convenient position.

Assuming the mail box to be empty, the parts will lie in the position represented in Fig. 1 with both openings closed, the flag 20 depressed and the weighted rod 16 held in horizontal position by the spring catch 18. If mail is to be deposited in the box, either by carrier or the owners of the box, the catch 18 is moved to disengage the rod 16 25 so that the weight 17 thereon will drop immediately and turn the closure 9 into the position represented in Fig. 2. A stop 26 projects from the bottom of the casing 1 against which the rod 16 strikes and limits 30 the movement of the closure 9. The oscillation of the closure 9 elevates the signal flag to the top of the mail box where it will be in full view of the carrier and others. When the mail is to be collected the closure 35 10 is unlocked, the hasp 20 raised and, grasping the staple 22 with the fingers, the closure is turned a half revolution as indicated in Fig. 4 entirely uncovering the collecting opening 11. During the movement 40 of the closure 10, after it has been turned through an arc of ninety degrees or half the distance, the staple 22 will strike the straight edge of the closure 9 as shown in Fig. 3 and carry said closure with it until 45 the arm 16 is again caught by the spring catch 18. The mail is then removed from the box and only the closure 10 returned and locked, leaving the closure 9 covering the deposit opening 6 and the signal flag 15 50 lowered.

From the above description it will be readily understood that before any mail can be deposited in the box the signal flag is automatically set and remains in sight, unless purposely lowered, until the box is 55 opened for collection, which latter action in turn automatically lowers the signal flag and closes the deposit or letter drop opening which remains closed until again opened in 60 the usual manner to receive mail.

Having described my invention, what I claim as new and desire to secure by Letters Patent is:

1. A mail box comprising a cylindrical receptacle permanently closed at one end and

having a fixed plate extending across the opposite end there being a deposit opening above and a collecting opening below said plate, a closure for said deposit opening carrying a visual signal and a closure for 70 said collecting opening adapted to operate the deposit closure when opened, said closures rotating on a common axis.

2. A mail box comprising a cylindrical receptacle permanently closed at one end and 75 having a fixed plate extending across the opposite end and of such width as to leave an upper and a lower opening in said end, a closure for the upper or deposit opening axially pivoted on the outside of said plate 80 and carrying a visual signal and a weighted rod, and a closure for the lower or collecting opening pivoted on the inner side of said fixed plate and on the same axis as the outer closure and disposed, when opened, to shift 85 the outer closure into position to cover the deposit opening and lower the visual signal.

3. A mail box closed at one end and having a mail deposit opening and a mail-collecting opening at the other end, a closure 90 for the deposit opening having a visual signal attached thereto and a weighted arm projecting in a direction opposite said signal, an arm-engaging catch on the box and disposed to hold the closure in closed position and the signal lowered, and a closure for said collecting opening having means thereon for moving said deposit closure into closed position while uncovering the collecting opening. 95

4. A mail box, closed at one end and partly closed by a vertical plate at the opposite end to form a deposit opening above and collecting opening below said plate, a closure for each opening having a common 105 axis of rotation, a weighted arm and a visual signal movable with the closure of the deposit opening, an arm engaging catch on the box and disposed to hold the closure of the deposit opening in a predetermined position, 110 and means actuated by the opening of the closure of the collecting opening for shifting the other closure into closed position.

5. A mail box, closed at one end and having a fixed vertically disposed plate extending across the opposite end above which is the deposit opening and below which is the collecting opening, a semi-circular plate for closing the collecting opening having a portion of one side removed and said plate being pivotally connected to the outside of said fixed plate, a catch on the mail box, a visual signal and a weighted arm movable with the closure plate and diametrically disposed, said weighted arm being disposed to 115 engage the catch to hold the closure plate in closed position and the signal lowered, said weighted arm, when released, operating by gravity to shift the closure plate into open position and to raise said signal and a 120 125 130

semi-circular plate pivoted to the inner side of said fixed plate for closing said collecting opening.

6. A mail box having a fixed vertically disposed plate extending across one end to divide the same into a deposit opening and a collecting opening, a semi-circular closure plate for the deposit opening pivoted to said fixed plate and rotatable in its own plane 10 and having a portion of one side removed, a visual signal and a weighted rod fixedly connected to and projecting in diametrically opposite directions from said closure plate said weighted rod adapted to hold the closure plate normally opened and the visual signal displayed, a spring catch on the mail box for engaging said weighted arm and retaining said closure plate over the deposit opening and the signal lowered, and a semi-circular pivoted closure plate for closing the collecting opening.

7. A mail box having a deposit opening and a collecting opening, a semi-circular closure plate for each opening rotatable in their own planes on a common axis, a visual signal on one plate, means for turning said plate on its axis to uncover the deposit opening and display said signal, means on the other plate adapted when said plate is moved

into open position to shift the first named 30 plate and close the deposit opening and lower the signal, a catch for holding the signal lowered and the deposit opening covered and means for locking the cover plate for the collecting opening when in closed position. 35

8. A mail box having a receiving opening and a collecting opening, separate closures therefor, gravity operated means upon one of the closures for holding the same normally in open position, and means movable 40 with the other closure during the opening thereof for shifting the gravity controlled closure into closed position.

9. A mail box having separate openings therein, a gravity controlled closure for one 45 of the openings, a normally upstanding signal carried thereby, a closure for the other opening, and means operated by said closure during the opening thereof for shifting the gravity controlled closure out of normal position and lowering the signal.

In testimony that I claim the foregoing as my own, I have hereto affixed my signature in the presence of two witnesses.
